UNITED STATES PATENT OFFICE.

EDWARD H. McCLOUD, OF COLUMBUS, OHIO.

DOOR.

1,285,285.

Specification of Letters Patent. Patented Nov. 19, 1918.

Application filed March 20, 1916. Serial No. 85,258.

To all whom it may concern:

Be it known that I, EDWARD H. McCLOUD, a citizen of the United States, residing at Columbus, in the county of Franklin and

5 State of Ohio, have invented a certain new and useful Improvement in Doors, of which the following is a specification.

This invention relates to the type of door that includes two sections, one of which is 10 slid up in front of the other, the two sections being then tilted together from the door opening to horizontal position, and the object of the invention is to provide a simplified and improved construction of this type 15 whereby its operation is made easier and more efficient.

This invention is embodied in the example shown in the accompanying drawings, set forth in the following description and finally 20 claimed.

In said drawings—

Figure 1 is a view in elevation looking at what is ordinarily the inner side.

Fig. 2 is a vertical section on the line 25 III—III Fig. 1 looking to the left.

Fig. 3 is a horizontal section on the line I—I Fig. 1.

Fig. 4 is a similar section on the line II—II Fig. 1.

30 In the views 5, 5 designate vertical channels or guides which are to be suitably secured to the vertical portions of the door way casing. 6 designates the lower door section or panel and 7 the upper door section or 35 panel. The lower corners of the lower section or panel 6 are each provided with rollers 8 journaled in brackets 9; and connected with said brackets are chains or cords 30 passing upward over suitable pulleys 10 and 40 11 to a counter balancing weight 12. The upper corners of the lower section or panel are each also provided with a roller 13 for the purpose to be hereinafter referred to.

The upper section or panel 7 is supported 45 by means of flanged rollers 14 journaled on bearings projecting laterally from the upper corners of that section, said rollers resting and traveling, as hereinafter described, on tracks 15 projecting horizontally from the 50 wall. The journals of the rollers 15 are conveniently supported on brackets 18 fastened to the upper corners of the upper section, said brackets formed to constitute stops against which the lower section abuts when 55 the latter is raised. The vertical edges of the upper section are provided with angle

bars 17 having one web offset from the face of the section so as to form channels or guides in which the vertical edges of the lower section travel when that section is 6 raised. When the lower section is raised to the position where it substantially coincides horizontally or is opposite the upper section it is stopped by means of the stops 18 before referred to fixed to the upper portion of the 65 upper section so that the two sections are coupled for further movement together in the same direction.

Brackets 16 secured to the wall and having 70 curved grooves 19 are provided and so positioned that when the lower section and the wheels 13 are raised the upper rims of said grooves cause the coupled sections to be deflected outward at their upper portions.

The upper section 7 is provided at each of 75 its upper corners with a latch pivoted at 21, said latch having an arm 22 to engage a shoulder 23 on the bracket 16 when the upper section 7 is in vertical position and a dependent arm 24 having a downwardly and 80 outwardly inclined end 25. When the lower section is raised the bearings of the rollers 13 strike the inclined ends 25 and raise the latching arm 22 thereby releasing the upper section permitting it to be deflected outward 85 from the wall with the lower section, the lower section being directly deflected by the engagement of the rollers 13 with the curved grooves 19. The upper wall of the groove 19 thus causes initial outward deflection of the 90 upper portions of the coupled sections but after some considerable deflection the upper portions of the coupled sections are supported by the flanged rollers 14 on the upper section traveling on the tracks 15 which support the sections at those portions while the lower portions are supported by the chains or cords, as indicated by broken lines Fig. 2. By raising the lower portions of the coupled sections sufficiently they can be brought to 100 substantially horizontal position. To permit the deflection of the sections at the upper portions of the channels the latter, at those portions, are cut away and made narrower as seen at 5^a.

105 The character 26 designates an endless chain running over a sprocket wheel 27, the shaft of which has a spur gear 28 to engage a spur gear 29 on the shaft of the pulley 11. By these or other familiar means the door, 110 when heavy, can be conveniently opened and closed. To close the door the operation is

merely reversed. When the coupled doors first reach the vertical position the latch drops to latching position after which the lower section descends by gravity or otherwise as may be desired to close the lower portion of the opening.

The forms of the parts can be changed without departing from the gist of the invention as claimed. For example the angle bars 17 need not be continuous and the function which they perform can be performed by several narrow pieces or fingers such as indicated by broken lines at 17^a Fig. 1, placed along the edges of the upper section.

15 What I claim is—

1. A door including, in combination, upper and lower sections, means for actuating them, means on one of the sections for holding them in sliding relation to each other, 20 means for coupling the sections to move together when in face to face relation, a guide for deflecting the upper ends of the sections operative in advance of the operation of said

coupling means, means on the lower section for engaging said last named guide, a track 25 projecting from the wall adjacent the door opening, and means on the upper door section for supporting the deflected door sections on said track.

2. A door including, in combination, upper and lower door sections, means for actuating them in parallel relation, guides for holding said sections in parallel relation, means for latching the upper section in vertical position, said latching means actuatable 35 by the lower section when raised, means for stopping relative parallel upward movement of the sections when the lower section is raised, means for deflecting the door sections from the door opening in advance of the operation of said stopping means, a track projecting from the wall adjacent the opening and means for supporting the door sections on said track when deflected from said door opening.

EDWARD H. McCLOUD.
